US00D994484S

(12) **United States Design Patent** (10) Patent No.: **US D994,484 S**
(45) Date of Patent: **** Aug. 8, 2023**

(54) **PACKAGING**

(71) Applicant: **Philip Morris Products S.A.**,
Neuchâtel (CH)
(72) Inventor: **Emmanuelle Clement**, Lausanne (CH)
(73) Assignee: **Philip Morris Products S.A.**,
Neuchâtel (CH)
(**) Term: **15 Years**

(21) Appl. No.: **29/789,159**

(22) Filed: **Sep. 3, 2021**

(30) **Foreign Application Priority Data**

Mar. 19, 2021 (EM) 008468821-0001

(57) **CLAIM**

The ornamental design for packaging, as shown and described.

DESCRIPTION

FIG. 1 is a front, top, and left side perspective view of packaging showing the new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.

The broken lines depict portions of the packaging that form no part of the claimed design.

1 Claim, 7 Drawing Sheets
